CLAIM

The ornamental design for a pet chew, as shown and described.

DESCRIPTION

FIG. 1. is a front, elevational view of my pet chew

FIG. 2. is a top view of my pet chew

FIG. 3. is a left view of my pet chew

FIG. 4. is a right view of my pet chew

FIG. 5. is a perspective view of my pet chew

FIG. 6. is a bottom view of my pet chew

FIG. 7. is a rear view of my pet chew; and,

FIG. 8. is a cross-sectional view thereof taken along line
8—8 in FIG. 1.

My pet chew is characterized by four legs, the bottom three
being separated from each other by approximately equal
angles, and separated from the top leg by approximately 109
degrees.
